CLAIM

The ornamental design for a magnetic bracket for mobile phones as shown and described.

DESCRIPTION

FIG. 1 is a front, left, and top perspective view of the magnetic bracket for mobile phones, showing my new design;

FIG. 2 is a rear, right, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view of the magnetic bracket for mobile phones of FIG. 1 shown in a state of use; and,

FIG. 10 is a front perspective view of the magnetic bracket for mobile phones of FIG. 1 shown in another state of use. The broken lines depict portions of the magnetic bracket for mobile phones that form no part of the claimed design.

1 Claim, 10 Drawing Sheets
